UNITED STATES PATENT OFFICE.

GEORGE J. HANLON, OF LONG ISLAND CITY, NEW YORK, ASSIGNOR OF ONE-HALF TO
JOHN A. MURRAY, OF FLUSHING, NEW YORK.

CLAMP AND BRACE FOR STAGE WINGS.

1,419,848.

Specification of Letters Patent. Patented June 13, 1922.

Application filed March 18, 1921. Serial No. 453,260.

To all whom it may concern:

Be it known that I, GEORGE J. HANLON, a citizen of the United States, and a resident of Long Island City, borough of Queens, 5 county of Queens, and State of New York, have invented a new and Improved Clamp and Brace for Stage Wings, of which the following is a full, clear, and exact description.

10 This invention relates to stage settings or scenery and has particular reference to a clamp and brace for stage wings.

Heretofore it has been the practice to secure the wings together and to the floor by 15 toe-nailing and to brace the same by nailing the braces to the wing frames and to the floor. It is obvious that such a practice not only requires a longer time to set up the wings but minimizes the length of service 20 thereof due to the constant wear to which the frames are subjected by the nailing operation.

The invention contemplates and seeks for 25 one of its principal objects to obviate the above recited objections by providing a clamp and brace which greatly facilitates the erection of wings without resorting to the use of nails.

A further object resides in the provision 30 of means for assembling the wings which means operates to retain the faces of the same flush and in correct alignment.

A still further object in view is to provide 35 a combination clamp and brace for stage wings which is capable of folding when not in use whereby the same can be stored in a minimum amount of space.

A still further object in view is to provide 40 a combination clamp and brace which is extremely simple in construction, inexpensive to manufacture and which is thoroughly reliable and highly efficient in its purpose.

With the above recited and other objects 45 in view, the invention resides in the novel construction, combination and arrangement of parts set forth in the following specification, pointed out in the appended claims and illustrated in the accompanying drawings, in which;

50 Figure 1 is a perspective view of a setting illustrating the wings thereof secured together and braced by the combination clamps and braces constructed in accordance with the invention.

55 Figure 2 is an enlarged fragmentary rear

view illustrating a single brace and clamp in its applied position.

Figure 3 is an enlarged horizontal sectional view taken approximately on the line 60 3-3 of Figure 2.

Figure 4 is an enlarged fragmentary side elevation illustrating the application of the brace and clamp.

Figure 5 is an enlarged fragmentary side elevation illustrating the supplemental brace 65 connection between the main braces and the wings.

Referring to the drawings by characters of reference, W designates the wings commonly employed in motion picture studios, 70 each of which comprises a wooden frame 10, the front face of which is covered by beaver board 11. The wings as illustrated are made in various heights and have heretofore been assembled by toe nailing the frames together 75 and nailing the same to the floor. The braces under the general practice have been nailed to the frames and toe nailed to the floor. To utilize the improved form of the clamp and brace in lieu of the usual nailing operation, 80 the side rails of the frames are provided with spaced apertures 12.

The clamp and brace constituting the invention consist of clamping pins 13 having 85 one extremity pointed as at 14 and provided adjacent the opposite extremity with a rectangular head 15 from which said extremity projects to constitute a trunnion 16. The head 15 may be constructed as a separate element secured to the pin or may be formed 90 integral therewith as desired. The pin is provided adjacent the tapered or pointed extremity 14 thereof with a longitudinal slot 17, the outer end wall 18 of which is of arcuate formation. Preferably apertured 95 wear plates 19 are secured over the apertures 12 with the openings therein in alignment therewith. A wedge 20 having an inclined outer edge 21 is designed to be driven 100 through the slot 17 after the pin 13 has been passed through the adjacent side rails of the wings. The inclined outer edge 21 of the wedge will engage and co-act with the arcuate end wall of the slot whereby contact 105 with the axial central point of the pin will produce an even axial strain when the wedge is inserted to draw the wings together.

The main brace members 22 are constructed in various lengths and each of said brace members is apertured at its upper end as at 110

23 to receive the trunnion 16 of the pin. The trunnion is apertured for the reception of a cotter pin 24 whereby the main braces are pivotally attached to the wings. The 5 braces are preferably constructed from angle iron and the flanges at the lower extremity thereof are separated and bent outwardly to provide apertured bearing feet 25 which contact with the floor and receive nails 10 or other fastening elements which are driven therethrough to secure the same in place. Supplemental brace bars 26 are employed for the purpose of connecting the main braces with the wings between their point 15 of connection with the wings and the floor. As illustrated in Figure 5 of the drawings, the supplemental brace bars 26 are longitudinally slotted as at 27 to receive a rivet 28 passed through said slot and one of the 20 flanges of the main braces 22. The outer extremity of the slot is offset as at 29 to contact with the rivet when the supplemental brace bars are arranged in operative position whereby to prevent relative movement 25 therebetween. The opposite end of each of the supplemental brace bars is apertured as at 30 and adapted to receive one of the trunnions after which a cotter pin 24 is passed through the apertured end of the trunnion 30 to retain said brace bar thereon. As heretofore stated the wings are of various heights ranging from 10 to 18 feet. The difference in height of each wing is approximately two feet and the apertures 12 are preferably 35 arranged one foot from either end of the wings with the intervening apertures spaced two feet apart. By this arrangement, in building up a setting the apertures 12 will be approximately two feet apart whereby the 40 wings may be universally assembled.

From this arrangement it is obvious that the wings may be assembled, set up and braced without the use of nails except those which are employed to secure the feet 25 to 45 the floor. When so set up the setting will be rigid and secure, will require less time to take down and due to the fact that the use of nails is not resorted to, the wings will last indefinitely. When it is desired to re-50 move and store the braces 22, it is only necessary to remove the cotter pins 24 and the nails which secure the feet 25 to the floor. The supplemental brace bars are shifted to disengage the offset 29 from the 55 rivet 28 and are swung parallel to the main parts where they are shifted longitudinally to lie within the confines of the same. If desired chains or other flexible fastening 60 means may be employed to secure the wedges 20 and bolts 13 to the wing frames adjacent each aperture.

While there has been illustrated and described a single and preferred embodiment of the invention, no limitation is necessarily 65 made to the precise structural details, as it

is to be understood that variations and modifications which properly fall within the scope of the appended claims may be resorted to when found expedient.

I claim:

1. A clamping and bracing means for the wings of stage settings including spaced apertured portions in said wings adapted to be brought into registration when the wings are contiguously arranged, retaining devices 70 insertable through said registered apertured portions having elements at the opposite ends thereof engageable with the wings for retaining the same against relative separation, and means adapted to be associated 75 with the retaining devices and the stage or support for the wings for bracing and supporting the same.

2. The combination with stage wings including frames and panels supported thereby, of means for detachably associating said wings with each other comprising apertured portions in the side rails of the frames adapted to be brought into registration when the wings are contiguously arranged, and 85 clamping devices adapted to be passed through said registered apertured portions including a shank having means at the opposite ends for engagement with the outer 90 sides of the side rails of the frames.

3. In a means for detachably associating the wings of stage settings, spaced apertured portions in said wings adapted to be brought into registration when the wings are contiguously arranged, retaining devices 100 comprising pins each having a head and slot respectively adjacent the opposite extremities thereof and wedges insertable through said slots for co-acting engagement with the wings to retain the same against 105 relative separation after the pins have been passed through apertured portions.

4. In a means for detachably associating the wings of stage settings, spaced apertured portions in said wings adapted to be brought 110 into registration when the wings are contiguously arranged, retaining devices comprising pins each having a head and slot respectively adjacent the opposite extremities thereof, wedges insertable through said 115 slots for co-acting engagement with the wings to retain the same against relative separation after the pins have been passed through apertured portions, in combination with brace members adapted to be associated 120 with said pins and disposed at an angle with respect to said wings for supporting and bracing the same.

5. Means for detachably associating the wings of stage settings and supporting and 125 bracing the same, comprising spaced apertured portions in said wings adapted to be brought into register when the wings are contiguously arranged, retaining pins insertable through said registered apertured 130

portions having fixed heads adjacent one extremity and means adapted to co-act with the opposite extremity and the wing for clamping and retaining the wings against relative separation, the opposite extremity of said pin constituting a trunnion, and apertured brace bars detachably associated for pivotal movement with said trunnions, the opposite ends of said brace bars being 10 designed to be fastened to the floor.

6. Means for detachably associating the wings for stage settings and supporting the same comprising in combination with wings having spaced apertures in the side rails 15 of the frames thereof, retaining pins insertable through said apertures when registered, said pins having heads at one end and means adapted to co-act with the opposite end and the frame rail for clamping and retaining 20 adjacent wings together, a trunnion projecting outwardly from the headed end of each pin, a brace having an apertured upper end adapted to engage over said trunnion, means for retaining said apertured brace 25 end thereon and means pivoted to said brace and adapted to co-act with the trunnion of one of the retaining pins for maintaining the brace at an angle to the setting.

7. The combination with stage wings having spaced apertures in the side rails of 30 the frames thereof, of means for detachably associating the wings when contiguously arranged with the apertures in register and for supporting and bracing the same, comprising headed pins insertable through 35 said registered apertures, means adapted to co-act with the pins and the wings for retaining the latter against relative separation, and braces detachably and pivotally carried by said bolts. 40

8. The combination with stage wings having spaced apertures in the side rails of the frames thereof, of means for detachably associating the wings when contiguously arranged with the apertures in register 45 and for supporting and bracing the same, comprising headed pins insertable through said registered apertures, means adapted to co-act with the pins and the wings for retaining the latter against relative separation, braces detachably and pivotally carried by said bolts, and means 50 carried by the braces and adapted to co-act with one of the retaining pins for maintaining the braces at an angle to the wings. 55

GEORGE J. HANLON.
